DESIGN.

C. J. DIEGES.

RING.

APPLICATION FILED APR. 3, 1922.

61,035.

Patented June 6, 1922.

Inventor:
Charles J. Dieges
By his Attorney
David W. Gardner

UNITED STATES PATENT OFFICE.

CHARLES J. DIEGES, OF NEW YORK, N. Y., ASSIGNOR TO DIEGES & CLUST, OF NEW YORK, N. Y., A CORPORATION OF NEW YORK.

DESIGN FOR A RING.

61,035.

Specification for Design.

Patented June 6, 1922.

Application filed April 3, 1922. Serial No. 1,513. Term of patent 14 years.

To all whom it may concern:

Be it known that I, CHARLES J. DIEGES, a citizen of the United States, residing in the borough of Manhattan, city, county, and State of New York, have invented a new, original, and ornamental Design for a Ring, of which the following is a specification, reference being had to the accompanying drawing, forming a part thereof.

The figure is a top plan view of a ring, showing my new design.

What I claim is,

The ornamental design for a ring, as shown.

CHARLES J. DIEGES.
